UNITED STATES PATENT OFFICE

2,410,900

MOBILE STEAM GENERATOR.

Raymond B. Radbill, Moylan, Pa.

Application March 6, 1945, Serial No. 581,278

2 Claims. (Cl. 122—504.1)

1

The present invention relates to steam generators and it relates more particularly to new and improved more or less integral units adapted for mounting on a vehicle or the like and designed to generate superheated steam for delivery to separate heating systems or the like.

An object of the present invention is to provide a new and improved mobile steam generator. Another object of the present invention is to provide a compact more or less integral unit adapted for mounting upon the chassis of a truck or other vehicle and capable of quickly generating superheated steam for supply to a railroad tank-car steam coil or the like.

Other objects and advantages of the present invention are apparent in the following detailed description, appended claims and accompanying drawings.

As is well known, road tars and asphalts and other similar products are usually shipped in railroad tank-cars; the tank-cars being loaded while the material is relatively warm and appreciably fluid. These materials, however, upon cooling in the tank-car, tend to harden to a point at which they are semi-solid or plastic. In this state, they cannot be removed from the tank-car by ordinary pumping operations.

Accordingly, it is necessary to provide such tank-cars with built-in steam coils which are adapted to be connected to a source of high-pressure steam to heat up the contents (after the cars have reached their destination) to a point at which they are sufficiently fluid to be pumped out.

In the past, it has usually been necessary to unload such tank-cars at buildings having high-pressure steam generating systems and for this reason it has usually been impractical to direct the tank-cars to a point adjacent the road, etc. being constructed or repaired, as is the most economical and efficient way to deliver such road tars or asphalts, etc.

The present invention contemplates the provision of a new and improved compact and more or less integral unit which can be quickly installed upon the chassis of a standard auto truck or the like and which is adapted safely, quickly and efficiently to generate superheated steam; the novel mobile unit being adapted to be driven up to a tank-car standing in the vicinity of the road being built or repaired and being adapted to deliver superheated steam directly to the heating coils of the tank-car so that the tar or asphalt can be heated to a relatively fluid state to per-

mit its being pumped out and used directly on the road.

For the purpose of illustrating the invention, there is shown in the accompanying drawings one form thereof which is at present preferred, although it is to be understood that the various instrumentalities of which the invention consists can be variously arranged and organized and that the invention is not limited to the precise arrangements and organizations of the instrumentalities as herein shown and described.

Referring to the accompanying drawings in which like reference characters indicate like parts throughout:

15 Figure 1 represents a side elevational view of one embodiment of the present invention.

Figure 2 represents a top plan view of the steam generating unit of the embodiment of Figure 1.

16 Figure 3 represents an elevational view, on a somewhat enlarged scale, of the embodiment of Figure 1, but showing the other side of the unit; parts being broken away better to reveal the construction thereof.

Figure 4 represents a rear view of the embodiment of Figures 1 to 3 shown as it appears in use connected to a tank-car; parts being broken away better to reveal the construction thereof.

Figure 5 represents a vertical cross-sectional view, on an enlarged scale, of the novel steam-generating and super-heating coil forming part of the present invention.

Figure 6 represents a vertical cross-sectional view generally along the line 6—6 of Figure 5.

Figure 7 represents a vertical cross-sectional view generally along the line 7—7 of Figure 5.

35 In one embodiment of the present invention shown generally in Figures 1 to 7, I have shown an auto truck indicated generally by the reference character 10 and having a standard chassis

40 11 upon which the novel steam generating unit to be hereinafter described is adapted to be mounted.

The steam generating unit includes a frame 12 of structural steel or the like upon which all 45 of the parts of the unit are mounted with the exception of the fuel tank 13 which may be mounted directly upon the chassis forward of the frame 12 as shown in Figures 1 and 3.

Alternatively, it is possible to make the frame 50 12 somewhat larger and to mount the fuel tank 13 upon the frame.

The frame 12 may be rigidly connected to the chassis 11 by means of a plurality of shackles 14; it being possible to provide beams 15 intermediate the chassis 11 and the frame 12, if desired.

The steam generating unit includes a novel heating unit 16 to be hereinafter described in detail, an oil burner 17, a water tank 18 for supplying water to the heating unit 16, a low pressure air compressor or blower 19 for supplying air under pressure to the oil burner 17 and also for supplying air under pressure to the top of the fuel tank 13, a pump 20 for delivering water from the tank 18 to the heating unit 16, a power unit 21 for driving the blower 19 and the pump 20, and means to be hereinafter described for delivering superheated steam (generated by the heating unit 16) to the heating coils of a tank-car and for condensing the used steam and returning it to the water tank 18.

The power unit 21 may be any conventional type of internal combustion engine, having a 4-groove drive pulley 66.

The pump 20 may be any conventional type of water pump, as for example, a triplex water pump having a crankshaft 22, a flywheel 23 and a double-groove pulley 24.

The blower 19 is provided with a double-groove pulley 67; the blower 19 and the pump 20 being adapted to be driven by the power unit 21 through double V-belts 25 and 26 connecting the pulley 66 to the pulleys 67 and 24 respectively. The blower 19 is adapted to deliver air under relatively low pressure through a small line 27 to the top of the fuel tank 13; the air pressure thus created at the top of the fuel tank 13 serving to drive the fuel oil through the lowermost delivery line 28 to the burner 17.

Most of the compressed air from the blower 19 passes through the relatively larger air line 29 to the oil burner 17.

The water pump 20 is adapted to pump feed water from the water tank 18 through the line 30 and to deliver the water to the heating unit 16 through the line 31.

The water tank 16 is provided with an uppermost filling pipe 32 and a level gage glass 33.

The novel heating unit 16 forming part of the present invention includes a head 34 of ceramic heat-resistant material having an open-ended combustion chamber 35 therein; the nozzle 36 of the oil burner 17 being in line with the opening of the combustion chamber 35 and being adapted to blow the combustion gases thereto.

The head 34 is connected to the rear end of an elongated generally cylindrical horizontally-disposed heat-transfer chamber 37 of metal or the like through which the combustion gases pass, eventually to escape through a flue-opening 38 provided at the front end of the chamber 37.

Within the heat-transfer chamber 37 is disposed a continuous water-tube steam generating coil system which includes an outermost helical coil 39 fitting snugly within the chamber 37 and extending generally the entire axial dimension thereof.

As shown particularly in Figure 5, the rear end of the coil 39 extends downwardly and through the wall of the chamber 37 and is connected with the water delivery line 31.

The front end of the coil 39 is connected with the corresponding end of an inner superheating coil 40 disposed co-axially with the outer coil 39 but radially spaced appreciably therefrom.

The inner coil 40 extends rearwardly from its intake end and terminates substantially short of the rear end of the outer coil 39. The rear end of the coil 40 connects with one end of an innermost superheating tube system 41 which is made up of a plurality of spaced axially-extend-

ing tubes connected at their ends through which the steam passes back and forth to be superheated to the desired pressure of approximately 150 pounds per square inch.

The outlet end of the superheating system 41 passes upward and out through the flue-opening 38; a pop-valve or safety valve 42 being provided at the end thereof.

A high pressure flexible steam delivery pipe 43 is detachably connected to the valve 42 and is adapted to be connected to the intake opening 44 of the steam heating coil 45 of a tank-car 46.

A flexible return pipe 47 is adapted to be connected to the outlet opening 48 of the heating coils 45; the other end of the return pipe 47 being detachably connected to a return line 49 provided with a strainer 50 and leading to a conventional steam trap 51 wherein the condensed water is separated from the steam and returned to the water feed tank 18 through the line 52. A by-pass line 53 provided with a shut-off valve 54 connects the lines 49 and 52 so that the steam trap 51 can be by-passed by closing valves 55 on either side thereof and by opening the valve 54.

The fuel line 28 is provided with a manual adjusting and shut-off valve 56 adjacent the burner 17. Another manual valve 61 and a strainer 62 are provided at the other end of the fuel line 28 near the tank 13.

The fuel delivery line 28 is also provided with an automatic safety shut-off valve 57 which is spring-tensioned to closed position and which is provided with an outer arm or lever 58 to which one end of a wire or cable 59 extends; the other end of the wire or cable 59 being secured to the pop-valve 42 through a fusible metal link 60.

The lever 58 of the automatic valve 57 is normally held by the wire or cable 59 so that it maintains the valve 57 in open position (against the spring pressure thereof) to permit flow of fuel oil therethrough to the burner 17.

Should the temperature in the heating unit 16 rise too high (due to failure of the water supply system or to any other cause), the link 60 will melt and will release the wire or cable 59 which in turn will permit the automatic valve 57 to move to closed position thereby to shut off the flow of fuel to the burner 17.

Instead of being directly connected to the pop-valve 42, the fusible link 60 may be connected to the pipe intermediate the valve 42 and the innermost superheating tubes 41.

Shut-off valves 63 and 64 may be provided in the water lines 30 and 31 respectively, adjacent the pump 20.

The power unit 21, the blower 19 and the pump 20 may be installed within a weather-proof compartment 65 to protect them from the elements.

In operation, the novel mobile steam generating unit of the present invention will quickly supply superheated steam under appropriate pressure to the heating coils 45 of the tank-car 46 until the tar or asphalt has been heated sufficiently to render it relatively fluid whereupon it can be pumped out of the tank-car by any appropriate pump in conventional manner.

The return pipe 47, the return line 49 and the steam-trap 51 permit continuous return of the used steam to the water tank 18 so that it is not necessary to add water to the tank except at rare intervals.

Thus, the novel mobile steam generating unit of the present invention can be used at places where there is no city or other water supply.

The pop valve 42, the fusible link 60, the cable 59 and the automatic valve 57 provide a foolproof unit which cannot explode, since, when the temperature and pressure within the heating unit 16 become excessive, not only is the pop valve opened to release the steam, but also the automatic valve 57 is closed to shut off the oil burner 17.

Where two or more cars are provided with inter-connected steam heating systems, they can 10 all be heated simultaneously; the delivery pipe 43 being connected to the first car and the return pipe 47 being connected to the last car.

While the novel mobile steam generating unit of the present invention is intended primarily for 15 use in heating road tar, asphalt and other bituminous products, it can be used equally well with other petroleum derivatives such as Amiesite, or with molasses or other products requiring heat.

The novel mobile steam generator of the present invention can also be used wherever high pressure steam is required remote from fixed steam and/or water supply; as for example, in 20 thawing manholes or culverts, cleaning drums, tanks or other equipment, soil sterilization, gas displacement (preliminary to welding, for example), etc.

The novel unit of the present invention generates steam almost immediately upon lighting of the oil burner and the ratio of weight to steam 30 generating capacity is extremely low.

The present invention may be embodied in other specific forms without departing from the spirit or essential attributes thereof, and it is therefore desired that the present embodiment be considered in all respects as illustrative and not restrictive, reference being had to the appended claims rather than to the foregoing description to indicate the scope of the invention.

Having thus described the invention, what I 40 claim as new and desire to protect by Letters Patent, is:

1. In a mobile steam generator adapted for mounting on an auto truck or the like, an oil burner, a fuel line leading to said oil burner, a heating unit disposed in operative juxtaposition

to said oil burner and including a combustion chamber and an elongated heat-transfer chamber communicating with said combustion chamber, a closed coil system disposed within said heat-transfer chamber, said coil system including a relatively long outer coil, a shorter coil disposed generally coaxially within said outer coil and spaced substantially radially therefrom and a series of innermost generally axially-extending superheating tubes, means for forcing water through said outer coil, said inner coil and said innermost tubes successively, said water being converted to superheated steam therewithin, a steam delivery line leading from said coil system and having a safety valve adapted to relieve excessive steam pressure, an automatic shut-off valve operatively connected within said fuel line, and means including a fusible metal link positioned adjacent said steam delivery line for closing said automatic shut-off valve when the temperature of said steam delivery line exceeds a predetermined value.

2. In a mobile steam generator adapted for mounting on an auto truck or the like, an oil burner, a fuel line leading to said oil burner, a heating unit disposed in operative juxtaposition to said oil burner and including a combustion chamber and an elongated heat-transfer chamber communicating with said combustion chamber, a closed coil system disposed within said heat-transfer chamber, said coil system including a relatively long outer coil, a shorter coil disposed generally coaxially within said outer coil and spaced substantially radially therefrom and a series of innermost generally axially-extending superheating tubes, means for forcing water through said outer coil, said inner coil and said innermost tubes successively, said water being converted to superheated steam therewithin, a steam delivery line leading from said coil system and having a safety valve adapted to relieve excessive steam pressure, an automatic shut-off valve operatively connected with said fuel line, and means for closing said shut-off valve upon 45 overheating of said coil system.

RAYMOND B. RADBILL.
